FIG. 4

A schematic diagram of a three-junction solar cell. It shows a top layer of p-type material (labeled 'p') with a central n-type region (labeled 'n'). Below this is a bottom layer of p-type material (labeled 'p'). The central n-type region is connected to an external circuit through a top contact and a bottom contact.

UNITED STATES PATENT OFFICE.

FRED MAARALA, OF NEGAUNEE, MICHIGAN, ASSIGNOR OF ONE-EIGHTH TO CHARLES PEKURI, OF BEACON, MICHIGAN.

ROTARY WASHING-BRUSH.

1,185,421.

Specification of Letters Patent. Patented May 30, 1916.

Application filed June 25, 1915. Serial No. 36,266.

To all whom it may concern:

Be it known that I, FRED MAARALA, citizen of the United States, residing at Negaunee, in the county of Marquette and State of Michigan, have invented certain new and useful Improvements in Rotary Washing-Brushes; and I do hereby declare the following to be a full, clear, and exact description of the invention, such as will 5 enable others skilled in the art to which it appertains to make and use the same.

This invention is an improved rotary washing brush or washing machine for use for washing windows, automobiles, rugs and 15 the like, the object of the invention being to provide an improved machine of this kind embodying a brush and water power driven means for rotating the brush and supplying the same with water, and also for 20 mixing washing soda or the like with water and supplying the mixture to the brush.

The invention consists in the construction, combination and arrangement of devices hereinafter described and claimed.

25 In the accompanying drawings:—Figure 1 is partly an elevation and partly a vertical sectional view of a washing machine constructed in accordance with my invention, showing one arrangement of the brush and 30 also showing the mixing mechanism. Fig. 2 is a sectional view of the same on the plane indicated by the line 2—2 of Fig. 1. Fig. 3 is a vertical sectional view showing another arrangement of the machine in which 35 the brush is connected directly to the mixing tank. Fig. 4 is a detail elevation, partly in section, showing the brush arranged for use without the mixing tank as for washing an automobile, buggy or the like. Figs. 5—6 40 are detail views.

In the embodiment of my invention I provide a mixing tank 1 in the bottom of which are a pair of strainers 2 of suitable mesh. A discharge pipe 3 leads from the 45 bottom of the tank and is connected thereto as at 4, at the center. A ring 5 is placed on the uppermost strainer 2 and fits snugly in the tank and on the said ring bears a disk 6 which is secured around the lower, open 50 end of a cylindrical screen 7, the said disk having an opening corresponding with the diameter of the screen and the latter having

a top 8 which is provided with a central opening.

A revoluble mixing shaft 9 has its lower 55 end mounted in a central opening in the screens and has its upper end mounted in a bearing in a bar 10 which bar is detachably fitted in bracket ears 11 in opposite sides of the mixing tank. The tank has a cover 12 60 detachably secured thereon by means of links 13 and levers 14 which are pivotally connected to the links as at 16 and pivotally mounted on opposite sides of the tank as at 17. The cover has a filler opening 18 and 65 a closure 19 screwed in said opening, this enabling the tank to be supplied with washing soda or other like material which is used for forming a washing solution.

A pipe 20 is detachably secured to the 70 lower end of the discharge pipe 3 of the tank by a T 21. A pipe 22 is connected to said pipe 20 by a T 23 and embodies an elbow 24 and a member 25, said member being connected by a coupling 26 to a pipe 27 which 75 is connected to the tank near one side and near the upper end thereof. The pipe 20 is connected by the T 23 to a pipe 28 which has a cutoff valve 29 said pipe being connected by an elbow 30 to a pipe 31 which 80 has a coupling 32 to enable any ordinary hose to be connected thereto.

A rotary water motor 33 is detachably connected to the upper end of the mixing shaft 9 and is arranged in the upper portion 85 of the tank and with one side presented to the pipe 27 so that water under pressure from said pipe 31 will be discharged in a jet against the motor and the latter rotated, thereby causing the shaft 9 to rotate in the 90 screen. Said shaft has stirring arms or mixing arms 34 which serve to thoroughly mix the washing soda or other material with the water in the tank 1 and hence supply the solution or mixture to the pipe 3. 95 I also provide a rotary brush 35 which is here shown as circular and the head of which has a central nipple 37 at the lower end of which is a rose 38 which extends down through a central opening in the head, 100 said nipple having a reduced threaded opening 39 near its lower end and having an enlarged threaded end 40 the upper side of which is beveled as at 41. A motor screw 42

is detachably threaded in the lower end of the threaded nipple and passes through and is revoluble snugly in a pipe 43 which is detachably connected by a coupling 44 to the 5 upper end of the nipple, said pipe having at its lower or outer end a coupling member 46 provided with a tapered end 47 which has a bearing in the beveled upper end of the nipple, said member having a bearing 10 in the coupling and hence the motor screw and the brush are arranged for rotation. The pipe 43 is detachably connected to the T 21 so that the motor screw is also partly arranged for rotation in the pipe 20. 15 Assuming that the water has been turned on in the hose, and that the valve 29 is open, the water passes through the pipe 20 and the pipe 43 and will act on the motor screw to revolve the latter and the brush, the water 20 also, by reason of the provision of the rose, serving to supply the brush, from the center of the latter. Water which passes through the pipe 22 and pipe 27 engages the rotor in the tank and revolves the rotor and the 25 stirrer, thereby causing the detergent material in the tank to be mixed with the water, the detergent mixture passing through the pipe 3 and T 21 to the pipe 43 and hence being also supplied to the brush. The brush 30 may be readily manipulated on any surface which it is desired to clean such as a window, automobile, buggy or other object.

In Fig. 3 of the drawings I show the rotary brush connected directly to the tank, 35 the pipes 20 and 22 being omitted and the pipe 28 being coupled directly to the elbow 24. In this arrangement of the device the pipe 43 is coupled directly to the pipe 3, the motor screw is disconnected from the brush 40 and removed and a mixing shaft 9^a of sufficient length is substituted for that shown in Figs. 1—2, said mixing shaft having its outer end threaded to the nipple of the rotary brush and its inner end connected to 45 the rotor. The brush will be revolved by the rotor as will be understood, the rotor also operating the stirring or mixing arms 9^b on the said shaft 9^a. The rotor shaft may be of any suitable length and may be made 50 of sections, detachably secured together as at 9^c, in Fig. 3.

In Fig. 4 of the drawings we show another arrangement of the invention in which the mixing tank is entirely omitted 55 and the pipe 43 is coupled to a tubular section 50 and said section 50 is connected to the outer end of the pipe 31 by an elbow 51. In this arrangement, which is especially adapted for use for washing automobiles 60 or buggies, the rotor screw is attached to the rotary brush 35 and operates in the pipe 43 and pipe section 50. The pipe 31 in addition to the coupling for connecting it to a hose is provided near its coupled end with 65 a T 52, the central arm of which is closed

by a suitable nipple plug to which an elbow 53 is screwed. A tubular socket piece 54 is screwed to the elbow and has a flared socket end 55 for the reception of a suitable handle 56 which is secured in said 70 socket, the handle being used to manipulate the brush as desired.

Having thus described my invention, I claim:—

1. In washing apparatus of the class described a tube arranged for coupling to a hose, a motor screw arranged for rotation in the tube, and a rotary brush mounted at the outer end of the tube and provided with means to convey water to the brush bristles 75 from said tube, the said motor screw being connected to said brush, and serving to revolve the latter, and said pipe being provided with means for the attachment of a handle thereto. 85

2. In a washing apparatus of the class described, a mixing tank, a rotor therein, mixing means in the tank including a revoluble element connected to and operated by the rotor, a discharge duct extending 90 from the mixing tank, a rotary brush connected to said discharge duct, a motor screw in said discharge duct and connected to the rotary brush to rotate the latter and a water supply pipe having a connection leading to 95 the mixing tank to rotate the rotor and supply the mixing tank with water and also having a connection leading to the discharge duct.

3. A washing machine comprising a mixing tank, a water supply pipe connected to the mixing tank adjacent the top thereof, a mixing shaft journaled in said mixing tank, a rotary water motor mounted on said mixing shaft adjacent the water supply pipe, a 100 cylindrical screen secured to said shaft, a discharge duct extending from said mixing tank, a rotary brush connected to said discharge duct and means for rotating said brush. 105

4. A washing machine comprising a mixing tank, a water supply pipe connected to said mixing tank adjacent the top thereof, a plurality of screens positioned within said mixing tank and provided with a central 110 aperture therein, a ring positioned within the mixing tank between the edges of the screen and the side walls of said mixing tank, a disk mounted upon said rings and provided with openings therein, a mixing shaft journaled in the bottom wall of the mixing tank and adapted to pass through the openings of the screens and said disk, a cylindrical screen mounted on said mixing shaft, means for rotating said mixing shaft, 115 a discharge duct connected to the bottom of said mixing tank, a rotary brush connected to said discharge duct and means for rotating said brush. 120

5. A washing machine comprising a mix- 125

ing tank, a water supply pipe connected to said mixing tank, a bar detachably mounted within said mixing tank adjacent the top thereof, said bar provided with a bearing 5 intermediate its ends, a mixing shaft journaled in the bottom wall of the mixing tank and into the bearing of the detachable bar, a cylindrical screen mounted on said mixing shaft, means for rotating said shaft, a 10 discharge duct connected to the mixing

tank, a rotary brush connected to said discharge duct and means for rotating said brush.

In testimony whereof I affix my signature in presence of two witnesses.

FRED MAARALA.
